UNITED STATES PATENT OFFICE.

GEORGE A. LONG, OF SCRANTON, PENNSYLVANIA.

ROTARY ENGINE.

1,334,252.

Specification of Letters Patent. Patented Mar. 16, 1920.

Application filed April 23, 1919. Serial No. 292,016.

To all whom it may concern:

Be it known that I, GEORGE A. LONG, a citizen of the United States, residing at Scranton, in the county of Lackawanna and 5 State of Pennsylvania, have invented a new and useful Rotary Engine, of which the following is a specification.

This invention has reference to rotary engines, and its object is to produce a rotary 10 engine which will work efficiently with any suitable motive fluid under pressure, such as air, gas, water, or steam.

In accordance with the invention, it comprises a stator and a rotor with the stator 15 inclosing the rotor and of considerably less width, while the rotor includes a circular course for fluid under pressure, which course is divided up by vanes into a circular series of pockets open at the periphery, 20 so far as the rotor is concerned, but having their size defined peripherally by the stator. The rotor has a lateral spread on each side of the stator and the fluid course about the rotor is of elliptical cross section with a 25 circumferential radial neck. The fluid under pressure enters the elongated pockets of the stator through the neck, into which suitable ports lead and which ports are arranged in opposite directions to cause the 30 reversal of the direction of rotation of the rotor. The spent material, after performing its work in the rotor, is directed into compartments gathering the spent material and arranged for its flow to a point of 35 position. The arrangement may be such that the fluid under pressure, after having passed through one engine, may be utilized in another lower pressure engine to drive it.

The invention will be best understood 40 from a consideration of the following detailed description taken in connection with the accompanying drawings forming part of this specification, with the understanding, however, that the invention is not confined to any strict conformity with the 45 showing of the drawings, but may be changed and modified so long as such changes and modifications mark no material departure from the salient features of the 50 invention as expressed in the appended claims.

In the drawings:—

Figure 1 is an elevation of one side of the engine, the engine shaft being shown in 55 cross section.

Fig. 2 is an end elevation of the engine

as seen from the right hand side of Fig. 1, showing the valve rod in cross section.

Fig. 3 is a vertical diametric section with some parts shown in elevation.

Fig. 4 is a vertical axial section with some parts shown in elevation.

Referring to the drawings, there is shown a base 1 which may be constructed similar to the showing of the drawings, or may be otherwise constructed as desired.

Fast to the base 1 are pedestals 2, 3 respectively, suitably spaced to receive the main portion of the engine and terminating at the upper ends in journal heads 4. Each 70 head 4 carries a curved plate 5, in turn supporting a roller cage 6, which latter may be of any approved form or may be replaced by a ball cage instead of a roller cage. A journal cap 7 is applied to the head 4 engaging the cage 6 on the side opposite the head 4, and clamp screws 8 serve to hold the parts in proper association. In order to adjust the plates 5, the head 4 has set screws 9 by means of which the antifriction 80 bearings 6 may be adjusted up and down as needed.

The bearings 6 carry a shaft 10 constituting the engine shaft and in turn supporting a rotor 11. To avoid inordinate weight 85 the rotor may be provided with radial spokes 12 carrying a rim 13 which, as best shown in Figs. 2 and 4, is relatively broad and correspondingly massive, the rim being broader than its radial extent. Within the rim there is provided a substantially elliptical channel 14 opening by a relatively narrow circumferential mouth 15 having side walls 16 projecting radially beyond the periphery of the body of the rotor. The 90 channel 14 is not a continuous channel throughout but is divided off into numerous sections by means of radial walls 17 constituting abutment plates completely filling the channel crosswise. The elliptical 100 cross sectional form of the channel 14 provides expansion space, especially for steam, so that the entering steam may have a jet action on the rotor through ducts or ports to be described.

Surrounding the rotor is a stator 18 of generally cylindrical shape and considerably narrower than the rotor so as to overhang, but to a little extent, the flanges 16 of the rotor. The stator is provided on each side 110 with a circumferential groove 19 with the inner walls of the groove about flush with the

outer walls of the flanges 16. Seated in the grooves 19 and against the flanges 16 are packing rings or gaskets 20 held in place by bolts 21, or in other manner, and clamps 22, whereby the joints between the rotor and stator may be rendered fluid tight. However, the arrangement is such that the packing rings while held tight to the stator do not press hard enough against the rotor flanges 16 to materially bind thereon.

Fast to the stator and preferably at a high point thereon is a valve chest 23 containing a slide valve 24 and connected to a pipe 25 for the introduction into the valve chest of fluid under pressure. Such fluid may be any fluid adapted for the purpose and steam may be taken as a convenient example of fluid under pressure and will hereinafter be considered as the motive fluid, without, however, any limitation to such particular fluid. The valve chest 23 is provided with a stuffing box 26 and the valve is connected to a valve rod 27 extending through the stuffing box. Leading from the valve chest 23 diagonally to the channel 14 are passages or ports 28, the passages being oppositely directed from an intermediate point of the valve chest so that either port may be utilized to conduct steam from the valve chest into the channel 14, but not both at the same time. The ports 28 are arranged substantially tangentially to the curvature of the channel 14 so that steam or other fluid under pressure entering the valve chest is directed against the blades or vanes 17 at about right angles thereto, whereby the force of the propelling fluid is exerted upon the vanes at the most advantageous angle.

Considering the valve chest and ports 28 as located at the upper part of the engine, although not necessarily so located, the casing 18 is provided diametrically opposite from the ports 28 with enlargements or expansions 29 each inclosing a chamber 30 with a relatively large mouth portion 31 and tapering to an outlet pipe 32 through which the used fluid under pressure may escape. Between the chambers 30 the casing has a circumferential continuation 33 separating one chamber from the other. The enlargements 29 drop below the casing continuation 33 and extending into the space between the enlargements 29 is a pedestal 34 constituting a support for the stator and rising from the base 1. Straps 35 are provided to hold the stator on the pedestal 34 and these straps are secured to the pedestal by bolts 36. Of course other means may be provided for the purpose.

When steam or other fluid under pressure is directed from the pipe 25 into the valve chest 23 it will find its way through one of the ports 28, say the left-hand port in Fig. 3, into the channel 14 and impinging against the vane 17 in its path. The result is that

the rotor is given an impulse to rotate in a left hand or counter-clockwise direction in the showing of Fig. 3. While the vanes are separated to a considerable extent circumferentially of the rotor they are sufficiently close together to prevent steam from passing directly from the port 28 to the chamber 30 in the direction of rotation. The pockets or compartments in the rotor are sufficiently extensive circumferentially to cause the impact of the fluid under pressure to continue its action throughout the greater portion of the distance between the intake port and the chamber 30 in order, so that any liability of dead space is reduced to a minimum. Moreover, the exhaust ports represented by the chambers 30 are elongated so that no material back pressure is established, or only such pressure is present in the chambers 30 and outlet pipes 32 as may be utilized to drive another similar engine of low pressure instead of high pressure type.

About one-half of the engine is utilized in the rotative effort in one direction so that the engine may be readily reversed by shifting the slide valve 24 to bring the other port 28 into action instead of the port first considered.

What is claimed is:—

1. A rotary engine comprising a stator with inlet ports therein and having enlarged chambers remote from the inlet ports to receive the spent fluid under pressure, and a rotor mounted concentrically with the stator and provided with a circumferential channel with blades separating the channel into sections, the rotor having the channeled portion expanded laterally beyond the side margins of the stator.

2. A rotary engine comprising a stator and a rotor mounted within it, the rotor having a circumferential channel of elliptical cross section with a radial mouth portion directed toward the stator and said stator constituting a closure for the mouth portion for a part of its length, the rotor extending laterally beyond the sides of the stator whereby to provide for inertia effect in the rim portion of the rotor despite the presence of the channel, and to permit reduction of the width of the stator.

3. A rotary engine comprising a stator and a rotor interior to the stator, the rotor being of greater width axially than the stator and provided with a rim having a laterally expanded channel therein opening circumferentially toward the stator and provided with division walls or blades in the channel to form circumferentially extended sections, the stator having means to direct fluid under pressure into the channel of the rotor and also having circumferentially extended outlets for spent fluid under pressure.

4. A rotary engine comprising a ring-

shaped stator with inlet ports and a valve controlling them, and also provided with enlarged outlet ports in remote relation to the inlet ports, and a rotor interior to the 5 stator, said rotor being wider than the stator and provided with a circumferential channel divided by equidistantly disposed radial blades or vanes into circumferentially elongated sections, the channel in the rotor being of greater width than height.

5. A rotary engine comprising a ring-shaped stator with inlet ports and a valve controlling them, and also provided with enlarged outlet ports in remote relation to 10 the inlet ports, and a rotor interior to the stator, said rotor being wider than the stator and provided with a circumferential channel divided by equidistantly disposed radial blades or vanes into circumferentially 15 elongated sections, the channel in the rotor being of greater width than height, and the channel in the rotor being also provided with a circumferential mouth portion of less width than the channel and opening 20 toward the inner wall of the stator.

6. A rotary engine comprising a stator and a rotor interior thereto, the stator having means for the passage of fluid under pressure to the rotor and with circumferentially 25 extended outlet ports and chambers of like extension into which the ports lead, with said chambers contracting to the outlet ends, and the rotor having a peripheral portion wider than the stator and containing a laterally widened circumferential 30

channel with a mouth portion opening toward the stator and with vanes or blades dividing the channel into sections, the blades being circumferentially spaced to cause a section of the channel to reach the discharge 40 port before the next succeeding section of the channel has passed the corresponding inlet port.

7. A rotary engine comprising a stator with inlet and exhaust ports on opposite sides, the exhaust being elongated circumferentially and enlarged into expansion chambers, and a rotor mounted interior to and concentric with the stator and provided with a circumferential channel with blades separating it into sections and said channel being expanded laterally beyond the side margins of the stator with the rotor also expanded laterally to provide an inertia rim, the channel in the rotor having a radial 55 mouth portion provided with side walls or flanges arranged on opposite sides of the body of the stator, and packing means carried by the stator in engagement with the side walls or flanges of the rotor with the 60 rim of the rotor extending laterally beyond the corresponding sides of the stator and the packing means.

In testimony that I claim the foregoing as my own, I have hereto affixed my signature.
